UNITED STATES PATENT OFFICE.

JOSEPH MYERS, OF MUSKEGON, MICHIGAN.

DESIGN FOR A PIN OR SIMILAR ARTICLE OF MANUFACTURE.

52,705.

Specification for Design.

Patented Nov. 19, 1918.

Application filed June 22, 1918. Serial No. 241,444. Term of patent 7 years.

To all whom it may concern:

Be it known that I, JOSEPH MYERS, a citizen of the United States, residing at Muskegon, in the county of Muskegon and State of Michigan, have invented a certain new, original, and ornamental Design for Pins or Similar Articles of Manufacture, of which the following is a specification.

The figure shown is a top plan view of a pin showing my new design.

The design consists of a pin or other similar article of manufacture, having a background of blue, indicative of the sea, with a large red cross centrally located thereon. The right arm of the cross having a representation of the old world, in colors, the left arm having a like representation of the new world. At the lower end of the lower arm

of the cross is a sinking ship, with the Statue of Liberty at the center of the cross and the American eagle immediately above it with outstretched wings extended over the old world and the new world, and the eagle proffering liberty to the old world. Above the eagle are thirteen red and white stripes, and the margin of the pin contains forty-eight stars upon a blue background, with the words: "In God we trust" above, and "Liberty to all" below the cross.

I claim:

The ornamental design for a pin or similar article of manufacture substantially as shown and described.

Signed at Muskegon, Michigan, June 13th, 1918.

JOSEPH MYERS.
